UNITED STATES PATENT OFFICE.

WILLIAM L. LANGLEY, OF NEWARK, NEW JERSEY, ASSIGNOR TO THE
ANGLEY COTTON HARVESTER COMPANY OF NEW YORK CITY.

PICKER-STEM FOR COTTON-HARVESTERS.

SPECIFICATION forming part of Letters Patent No. 372,919, dated November 8, 1887.

Application filed December 20, 1886. Serial No. 222,115. (No model.)

To all whom it may concern:

Be it known that I, WILLIAM L. LANGLEY, a citizen of the United States, residing at Newark, in the county of Essex and State of New Jersey, have invented certain new and useful Improvements in Picker-Stems for Cotton-Harvesters, of which the following is a specification.

This invention relates to a picker-stem for picking cotton from the bolls on plants in the field. Stems of this character are used on machines which are mounted on wheels to be moved in the field along a row of cotton-plants.

The invention is illustrated in the accompanying drawings, in which—

Figure 1 is a side view of the improved picker-stem. Fig. 2 is a longitudinal section of the improved picker-stem. Fig. 3 is a view of one tooth-plate in the finished condition ready to be secured in the stem. Fig. 4 is a cross-section of the core part and guard-plates. Fig. 5 is a view of the point-cap of the stem. Fig. 6 is a cross section of the stem. Fig. 7 is a view of the shank-head of the stem. Figs. 8 and 9 are views of the shank-fastenings. Figs. 10 and 11 are cross-sections of the stem and show modifications in the number and position of tooth-plates and the number and shape of the tooth-guards.

The letter *a* designates a longitudinal plate of suitable metal. This plate is flat, and one edge, *a'*, is straight and smooth, and the other edge, *a''*, is provided with inclined teeth *b*. The longitudinal tooth-plates are combined with longitudinal guard-ribs and arranged so that each tooth-plate, with its teeth pointing outward, shall be between two guard-ribs and form longitudinal spaces. The finished picker-stem therefore possesses the several features named. Of course there may be much variation in the construction for uniting these parts. One way only will here be described. The tooth-plates are secured to a central core part, *C*, provided with longitudinal guard-ribs *d* and longitudinal spaces *e*. In other words, the cylindric body may be said to be longitudinally corrugated or fluted, as seen in Fig. 6. The core part *C* may be solid or tubular, and the guard-ribs *d* may be integral with the core or may be separate parts attached to the

core. Between each two guard-ribs *d* the core has a longitudinal groove, *f*, which receives the smooth edge *a'* of the tooth-plate, leaving the teeth pointing outward, and projecting at each end of the core is a round journal end, *g*. Two caps, *I J*, are employed—one for the point end of the stem and one for the shank end. The point-head *I* has a central socket, *h*, which receives one journal end *g* of the core part, and also has radial grooves *a''*, each of which receives an end of one of the tooth-plates. The outer end of each radial groove is closed at *k* and forms a lip—that is, the grooves do not extend to the circumference of the head, and the said closed lip *k* takes over the outer edge of the tooth-plate and confines the said plate in the longitudinal groove *f*. The shank-head *J* has a central hole, *l*, for the shank *N*, a socket or enlargement, *h'*, around the said central hole for one journal end *g* of the core part, and radial grooves *a''* for the ends of the tooth-plates.

To assemble the several parts of the picker-stem, the tooth-plates *a* are set in the longitudinal grooves *f* so that the teeth shall point outward and incline toward the shank, and the caps *I J* are placed in position, as shown in Figs. 1 and 2, and secured by pins *m* or in any suitable way, whereby, as already described, the caps confine the tooth-plates. The picker-stem has a shank, *N*, which may be secured in any desired way. In the present instance the shank *N* has position in the end of the core part *C* and in the central hole, *l*, of the cap *J*. A spring is so combined with the picker-stem, its shank, and a holder as to form a flexible or yielding connection between the picker-stem and holder. The holder *O* is a suitable arm or plate constituting part of a machine not necessary to describe here. It is provided with a hole, *p*, for the shank *N* of the picker-stem, which latter fits loosely in the hole, in order thereby to permit the picker-stem to revolve, to move slightly endwise, and to allow the point end of the stem to move laterally in all directions. All of these movements, or either of them alone, are useful and desirable in the work that a cotton-picker stem has to do. The spring *Q* surrounds the shank, and one end bears against the holder *O* and the

other end takes effect on the picker-stem. In this combination the spring to be used may be either a spiral spring, Q, as shown in Figs. 1 and 2, or a rubber spring, Q', as shown in Fig. 9.

In the drawings two positions for the spring are shown. In Fig. 1 the spring is on the side of the holder most remote from the cap J of the picker-stem, and is interposed between the said holder and a disk, r, on the shank. In Figs. 2 and 9 the spring is on the side of the holder O nearest the head of the picker-stem, and in this instance is interposed between the said holder and head. The expansive tendency of the spring in the described combination serves to keep the picker-stem projecting horizontally, and at the same time allows its point end to move within certain limits either up, down, or sidewise.

20 A special novel construction in the said spring combination is shown in Figs. 2, 8, and 9. Here the spring may be either spiral metal or rubber. On the side of the holder most remote from the picker-stem cap J is a curved disk, s, the outer curved side of which is in contact with the holder O. Figs. 2 and 8 show the vertical position of this curved disk, and Fig. 9 gives a horizontal section of the same. A pin, t, passes vertically through the extremity of the shank N, and said pin is in contact with the straight part of the inner curved side of the disk. This device serves much better to sustain the picker-stem horizontally, while allowing freedom to move laterally. The 35 combination which includes the spring is not limited to the construction and arrangement of the tooth-plates, guard-plates, or spaces.

The picker-stem may have any desired number of tooth-plates and guard-plates. In Fig. 40 6 eight are shown, while in Fig. 10 four only are shown, and in Fig. 11 six are shown.

The longitudinal tooth-plates have been described and are hereinafter claimed as having "outward" or "radially" pointing teeth. It is 45 not essential, however, that they should be radial. Fig. 11 is illustrative of outward-pointing teeth which are not radial. In this case the teeth point outward, but incline tangentially.

A picker-stem having such teeth may revolve 50 or not.

This form of picker-stem will readily enter the plant, and the cotton which protrudes loosely from the bolls on the plants will be caught or hooked by the teeth, and when the back movement of the stem takes place the 55 cotton will be drawn out of the boll. The special guard-plates, while protecting the outward-pointing teeth, are so arranged as to form the longitudinal spaces e, which facilitates the engagement of the cotton on the teeth.

Having described my invention, I claim and desire to secure by Letters Patent of the United States—

1. A cotton-picker stem consisting of a core, C, end caps, I, J, and longitudinal tooth-plates 65 secured in grooves in the core of said stem, substantially as shown and described.

2. A cotton-picker stem consisting of a core having journal ends with end caps and longitudinal tooth-plates seated in grooves in said 70 core, a shank entering the core-stem, and a holder, O, substantially as shown and described.

3. In a cotton-picker stem, the combination of the core C, having guard-ribs d and journal ends g, with the caps I and J, having sockets h, the tooth-plate a, arranged longitudinally between the said guard-ribs d, having the spaces e on each side, all substantially as shown and described.

4. In a cotton-picker stem, the combination 80 of the core C, the end caps, I and J, having the radial grooves a', lips k, and the tooth-plates a, arranged and secured thereto, substantially as shown and described.

5. In a cotton-picker stem, the core C, having 85 longitudinal guard-ribs d, in combination with tooth-plates a, arranged between said guard-ribs, the shank N, the holder O, having opening therein, the spring Q between the holder and the base of the stem, and a pin on outer 90 end of said shank, all substantially as and for the purpose set forth.

In testimony whereof I affix my signature in the presence of two witnesses.

WILLIAM L. LANGLEY.
